UNITED STATES PATENT OFFICE

ALVIN O. OLAFSON, OF ST. PAUL, MINNESOTA, ASSIGNOR, BY DIRECT AND MESNE ASSIGNMENTS, TO NATIONAL TRAFFIC SIGNAL COMPANY, OF ST. PAUL, MINNESOTA. A CORPORATION OF MINNESOTA

TRAFFIC SIGNAL

Application filed November 18, 1927. Serial No. 234,168.

My invention relates to a signal particularly adapted to indicate the stop and go to traffic at intersections. A primary feature of the invention resides in a means adapted to indicate by a clearly visible means, the approximate time of the change of the traffic signal which is visible either in the daytime or at night to indicate the approximate time before the signal will change.

It is also a feature of the invention to provide means of a curtain-like nature which is adapted to be operated by time mechanism in a manner to cause the curtain to gradually shut off a light which indicates the change of the signal.

My signal includes a means of indicating on two or more sides a streak of light so as to indicate in accordance with the size of the streak of light how much time remains before the signal will change. As the signal approaches the changing period the signal light is gradually shut off until it is entirely invisible momentarily just as the signal changes to change the direction at street intersections.

I include in my invention a means of diffusing the light at a point adjacent the screening curtain which causes the curtain to give a clear shadow either during the day or at night, and even in the sunshine.

My signal includes a transmission which may be readily changed for different speeds together with a suitable timing means which may be adjusted or set as may be desired to change the time of the operating curtain signal.

I also provide means for damping the drop of the curtain which is an important feature of my invention.

These objects, together with other details and features will be more fully and clearly set forth in the specification and claims.

In the drawings forming part of my specification:

Figure 1 indicates a perspective view of my signal as it would appear in use.

Figure 2 is a detail of a portion of the same. Figure 3 is a detail of a portion of my signal.

Figure 4 is a detail of the signal.

Figure 5 is a section on the line 5—5 of 50 Figure 4.

Figure 6 is a plan view of the signal head.

Figure 7 is a detail of one of the adjustable lifters.

Figure 8 is a side sectional view of my 55 signal.

Figure 9 is an enlarged detail partly in section.

Figure 10 is an enlarged detail partly in section.

Figure 11 is a cross section. 60

Figure 12 is a detail of a portion of the lifting chain and lifter.

My signal A is designed to provide an upright signal having side walls 10 and corner members 11. The side walls 10 are provided with signal indicating openings 12 and these openings may be formed in two or more sides of the side walls. The openings 12 may be covered with glass or other suitable material 65 to inclose the inner parts of the signal A. 70

The signal A is formed with a signal head B having openings 13 adapted to indicate the direction of travel of the traffic by suitable colors such as red and green, the red color 75 indicating a stop and the green the go, or the openings 13 may indicate the words "Stop" and "Go."

Within the sides 10 which form the casing with the corner members 11 I provide operating mechanism for the signal A. This operating mechanism includes a transmission C made up of a series of driving gears 15 which are mounted upon the shaft 16. These gears are adapted to be operated by the motor D 85 through suitable connecting gears as indicated in Figure 8. The gears 15 may be of different sizes and are collectively arranged on the shaft 16. By means of a jack shaft 17 mounted above the shaft 16 which is formed 90

with a long bearing or support 18, I provide a means of supporting the intermediate gear 19. The gear 19 is adapted to mesh with one of the gears 15 and by changing the size of the gear 19 as indicated in dotted outline on the shaft 5 17 the speed of the transmission C may be varied. The line of drive from the motor D extends through the gears 20 to the shaft 16 which in turn drives the shaft 17 through the 10 gears 21 and from thence through the gear 19 to one of the gears 15 which operates the gears 22. One of the gears 22 is connected by means of a sprocket 23 which drives the lifting chain 24.

15 I provide a suitable shelf 25 for the extra gears 19 so that my signal is all self-contained and any time that it is desired to change the speed of the operation of the same it is only necessary to take a different size gear 19 from 20 the shelf 25 and place it in the transmission C in such a manner as to mesh with the proper gear 15.

25 The lifting chain 24 travels from the sprocket 23 and over the idle pulleys 26 located near the top of the signal A. This lifting chain 24 is adapted to receive lifters 27 which include spring fingers 28 adapted to engage over the pins of the chain 24 as indicated in Figure 9 and which are provided 30 with a lifting roller 29. The lifters 27 can be snapped on to any link of the chain 24. Thus the lifters may be changed in position on the chain and by placing these lifters at different points on the chain the timing of 35 the curtain signal is regulated. This will be more fully hereinafter described.

40 I provide a series of electric lights 30 within my signal A which extend along the openings 12 so as to provide a sufficiently strong light for the openings 12 to provide an indicating light adapted to indicate the change of the signal. The lights 30 may be of a frosted nature, however, I prefer to provide translucent diffusing screen plates 31 spaced 45 from the lights 30 and which are hung from the top shelf 32 by means of the clasps 33 so that the translucent shields 31 will diffuse the light from the electric bulbs 30 in a proper manner within the signal A.

50 I provide a curtain 35 in my signal A which is adapted to act in a manner to shut off the light coming through the openings 12 in the operation of the signal A. The curtain 35 is operated by the lifters 27 which engage 55 against the shoulder member 36 formed at the top edge of the curtain 35. As the transmission C is operated and the lifting chain 24 carries the lifters 27 into engagement with the shoulder 36, the curtain 35 is lifted in a 60 manner to curtain off the light coming through the openings 12. The lifting chain 24 operates in a timed manner so as to slowly lift the curtain 35 and thus the signal light which is adapted to indicate the time of 65 change through the openings 12 is gradually

shut off as the curtain 35 is lifted. When the curtain 35 reaches its uppermost position the lifter 27 will automatically disengage the shoulder 36 and the curtain 35, which is made of aluminum or any other suitable material, 70 is adapted to fall or drop to the lower portion of the signal casing formed by the sides 10 and the corners 11.

75 I provide a check damper E for the curtain 35 which is indicated in Figure 10. This check damper E includes an operating arm 38 which is pivotally mounted to the face plate 39. One end of the check arm 38 is curved at 40 to form a bearing end which is adapted to engage against the leather cushion 41 which is attached to the inside of the curtain 35 on one side. The check E is formed with a spring 42 which normally holds the bearing end out of engagement with the side of the curtain 35. The bearing arm 38 is also formed with a brace portion 43 extending between the bearing end 40 and the free end 44. The curtain 35 is provided with a shoulder member 45 which is positioned in such a manner as to engage against the free end 44 of the arm 38 as the curtain 35 drops from its elevated position to its lowermost position. Thus as the curtain 35 falls to lowermost position it does not strike with its dropping force against the bottom of the signal A, but is engaged by the damper E in a manner to retard and damper the fall of the same just before the curtain strikes the bottom of the inside of the signal A, thus effectually retarding the drop of the curtain 95 and protecting the same against undue wear. The coil spring 42 releases the check E the moment the curtain is lifted by the lifter 27.

100 The retarder E prevents the rebound of the curtain 35 and virtually momentarily locks the same into lowermost position. The retarder E, however, is readily released upon the elevating of the curtain.

105 The lights through the openings 12 are adapted to provide signal lights indicating the change of the signal. The length of the light through the openings 12 indicates the approximate time of change of the signal A in proportion of the travel of the screening curtain 35.

110 The diffusing screen plates 31 may be easily removed by disengaging the same from the shelf 32 to replace the lights 30. These screens diffuse the light from the lamps 30 so that a sharp defined shadow or line is effected from the top edge 48 of the curtain 35 and appears through the openings 12 at night or even in the sunlight to clearly indicate the position of the curtain 35 in the signal A.

115 I provide a guard arm 49 in the curtain 35 which holds the chain 24 into engagement with the shoulder 36 even though the chain may vibrate some in its operation.

120 The signal head B is adapted to indicate 120

the stop and go of the traffic and this may be accomplished by color or by the wording itself. I have shown in the drawings a means of indicating the direction of travel in the head B. This includes a rotatable frame 50 which is supported within the head B by the shaft 51 upon which the frame 50 is adapted to rotate. The shaft 51 is held by the nut 52.

10 The frame 50 is adapted to support a series of lenses 53 which may be of red and green color or which may carry the words "Stop" and "Go" to indicate to the traffic the direction of travel and to indicate stop and 15 go of the same. The lenses 53 may be of a flexible nature such as celluloid or other suitable colored translucent material and may be held by the grooves 54 formed in the frame 50 so that the lenses 53 may be removed when 20 it is desired.

Within the frame 50 I provide an electric light socket 55 which is adapted to carry a signal light for the signalling head B to indicate the signal through the openings 13. 25 Figure 3 illustrates the head 50 with one of the lenses 53 removed so that the signal light can be placed within the socket 55.

The top of the frame 50 is formed with a collar having depending teeth 56 which engage against the pin 57 to direct the frame in a rotary movement as it is lifted on the shaft 51. One side of the teeth 56 inclines at an angle, while the other side is comparatively straight longitudinally with the 35 shaft 51.

The bottom of the frame 50 is provided with inclined arms 58 which are adapted to be engaged by the lifting pin 59 carried by the curtain 35, as the curtain is elevated. I 40 provide a guiding pin 60 projecting from the shelf 32 which holds the frame 50 against rotation in the first period of its lifting on the shaft 51 by means of the lifting pin 59. This pin 60 steadies the frame 50 so that it 45 will not bind on the shaft 51 and prevents rotation until it has been elevated to a predetermined point, so that when it is released from the pin 60, the arm 58, owing to the angular nature of the same, will cause the frame 50 to rotate on the shaft 51 and the inclined surfaces of the teeth 56 engaging against the pin 57 will cause the frame 50 to rotate a quarter turn, changing the position 50 of the lenses 53.

55 Thus as the curtain which indicates the time of change of the signal head B reaches its uppermost position shutting off the light from the windows or openings 12, the frame 50 is operated, operating the signal head B 60 to change the indicating direction to the traffic. It is therefore apparent that if the two opposite lenses 53 are green and the other two diametrically opposite lenses are red, that the signal head B will indicate through 65 the openings 13 "Stop" by the red light to one

direction of travel, and "Go" by the green light to the other direction of travel. It is further apparent that the curtain 35 will act in the sense of a thermometer indicator, gradually shutting off the light through the openings 12 so that as the motorist or pedestrian approaches the signal A they can see very clearly the approximate time of change of the signal A. The signal is adapted to operate automatically to change the direction indicator in the head B by means of the operation of the curtain 35. The change of the indicating head B is simultaneous with the operation of the curtain 35 at the moment the curtain reaches its uppermost position. The light from the openings 12 is only shut off momentarily and by means of my signal I believe a more practical indicator is provided than heretofore, by virtue of the time indicating curtain which indicates the approximate time of change of the signal head B. The position of the curtain indicates at all times the approximate time of change of the head B. The adjustment of the lifters 27 to different positions on the chain 24 permits the signal to be so set that the intervals between the time of lifting of the curtain 35 may be lengthened or shortened so that a longer or shorter time may be set for the travel of traffic in one direction or the other and the transmission C may be set to operate the signal slow or fast so that I provide a signal adjustable and variable as to speed and time in a very simple and effective manner.

It is an important feature of my invention to provide a means for indicating the time of change of the signal by a moving element which is clearly visible day or night and even in the sunlight. I accomplish this by the particular means set forth. I believe my signal in its simple operation and clearly visible thermometer-like indicator provides to the traffic a more simple and effective means of signalling. This is particularly true when considering that if the pedestrians and motorists know just exactly when the signal is going to change, less confusion will arise and thus I believe accidents may be avoided.

In accordance with the patent statutes I have described the principles of operation and I have set forth particular features, I desire to have it understood, however, that these are only illustrative of a means of carrying out the invention and that the same may be varied within the scope of the following claims without departing from the spirit of my invention.

I claim:

1. A signal including, a signalling means adapted to indicate stop and go, a change signal light, and a curtain for gradually shutting off said change signal light.

2. A signal including, stop and go indicating means, a change signal means, curtain means for gradually shutting off said

change signal means to diminish and completely shut off the same, means for releasing the curtain to permit the same to drop, and retarding means operable by the dropping force of the curtain to retard and prevent rebound of the same.

3. A signal comprising, a signalling standard, a signal adapted to indicate stop and go in said standard, a signal light associated with said stop and go, curtain means for gradually shutting off said signal light, and means for diffusing the signal light in a manner to cause a sharply defined shadow from the shutting off curtain.

15 4. A signal including, a casing, a signal head adapted to indicate stop and go, a change signal light associated with the stop and go signal, a curtain for shutting off the change signal light, and a transmission adapted to vary the speed of the operation of the curtain.

5. A signal including, stop and go means for signalling, a change signal light, a curtain for gradually shutting off said change signal light, means for operating said curtain at variable speeds, and means for retarding and preventing rebound of said curtain in the fall of the same.

6. A traffic signal including, a standard, a signal light at the top of said standard adapted to indicate stop and go, a change signal light below said stop and go signal means, a curtain for gradually shutting off said change signal light, and adjustable means for operating said curtain to vary the time of lifting the same to permit the curtain to be lifted in a manner so as to provide long and short intervals in the operation of the same.

7. A signal including, a stop and go signal light, a change signal light, a curtain for shutting off said change signal light, means carried by said curtain for operating said stop and go signal light to change the direction of traffic at the moment of said curtain reaching the limit of travel in one direction at the time of shutting off the change signal light, and means for timing the operation of said curtain to provide long and short intervals between the stop and go traffic.

8. A traffic signal comprising, a standard, a stop and go signal in the head thereof including a rotatable lens carrying member, means for operating said lens carrying member to rotate the same by lifting and cause the same to rotate when gravitating to normal position, and means for holding said lens holding member non-rotatably during the lifting operation thereof.

9. A traffic signal comprising, a rotatable lens member adapted to indicate stop and go by similar colors on diametrically opposite sides, and means for supporting said member to permit the same to be lifted, and then rotated to a changed position in its movement by gravity to normal position.

10. A traffic signal including, a signalling head, a signal change indicator associated with said signal head, a curtain for shutting off said change indicator, means for operating said signal head by said curtain, a changeable transmission for operating said curtain to vary the speed thereof, and an adjustable lifter adapted to be adjusted to vary the timing of the lift of said curtain means.

11. A traffic signal including, a signalling head, a signal change indicator, a curtain for screening the indicator, lights for illuminating the indicator, diffusing means interposed between the lights and curtain to cause the curtain to form a sharp defined line of indication at night and in the sunlight.

12. A traffic signal including, a signal light, a curtain for screening the light and means for diffusing the light in relation to the curtain so as to cause the curtain to be sharply defined in the outer appearance of the same in daylight and at night.

13. A traffic signal including, a signal light, a curtain for screening the light, and means for diffusing the light in relation to the curtain so as to cause the curtain to be sharply defined in the outer appearance of the same in daylight and at night.

14. A traffic signal including, a casing, a signalling means within said casing, a transmission within said casing, a motor for operating said transmission, a curtain surrounding said transmission and slidably positioned within said casing, a chain operable by said transmission, an adjustable lifter means carried by said chain adapted to engage said curtain to lift the same, said curtain being adapted to be timed by said transmission and lifting means to operate to screen off said signalling means.

15. A traffic signal comprising a casing, a signal head in the top of said casing, a signalling cylinder rotatably mounted in said head, a slideable curtain operable below said head, a transmission and lifting means adapted to operate said curtain, openings in said casing in said head to indicate the direction of travel of traffic, elongated openings below said head extending longitudinally of said casing which are adapted to be screened by said curtain in the operation thereof, means operable with said curtain and signalling cylinder adapted to cause said cylinder to operate simultaneously with said curtain at the uppermost position of said curtain to change said cylinder to indicate a change of traffic, and means adapted to retard the fall of said curtain and overcome the rebound thereof.

16. A signal for traffic including, a casing, a curtain within said casing, means for operating said curtain in a manner to elevate to a predetermined position, means for releasing said curtain causing the same to fall, and means for retarding the falling force of said curtain by changing the same in a manner to

prevent the curtain from dropping with undue force.

17. A traffic signal including, signalling means adapted to indicate stop and go, means adapted to indicate the time of change of said stop and go signal means including curtain means for screening said indicating means, means for operating said curtain in a manner to move the same to a predetermined position and release the curtain causing it to fall, and means adapted to retard the fall and rebound of the curtain when released.
